Patented Apr. 25, 1922.

UNITED STATES PATENT OFFICE.

ABRAHAM ZWIEBELSON, OF NEW YORK, N. Y.

BRASSIÈRE.

1,414,321.

Specification of Letters Patent. Patented Apr. 25, 1922.

Application filed December 6, 1920. Serial No. 428,505.

To all whom it may concern:

Be it known that I, ABRAHAM ZWIEBELSON, a citizen of the United States, and a resident of the city of New York, borough 5 of Manhattan, in the county and State of New York, have invented a new and Improved Brassière, of which the following is a full, clear, and exact description.

The object of the invention is to provide 10 a new and improved brassière arranged to insure accurate fitting on the wearer's body and to hold it against upward creeping and wrinkling particularly at the back.

Another object is to provide a smooth 15 foundation for the back of the outer garment to overlie, and to allow a proper fit of such garment mainly at the waist line to insure a proper hang of the outer garment.

With these and other objects in view, the 20 invention consists of certain novel features of construction as hereinafter shown and described and then specifically pointed out in the claims.

A practical embodiment of the invention 25 is represented in the accompanying drawings forming a part of this specification, in which similar characters of reference indicate corresponding parts in all the views.

Figure 1 is a rear perspective view of the 30 brassière as applied, part of the back being shown turned up;

Figure 2 is an inner side perspective view 35 of the brassière; and

Figure 3 is an enlarged sectional plan view of the same on the line 3—3 of Figure 2.

The body 10 of the brassière is preferably 40 made from a single piece of inelastic material, and the said piece is provided at the double-up ends with tapes 11 and 12 provided with coacting fastening members 13 and 14, such as hooks and eyes, to allow of closing the brassière at the back, as plainly shown in Figure 1. The top and bottom 45 edges of the body 10 are provided with suitable bindings 15 and 16, and shoulder straps 17 are attached to the upper edge of the body 10 at the top binding 16.

The body 10 is provided with permanent 50 integral folds 20, 21 of tapering form and extending from the top binding 16 to the bottom binding 15 and being spaced from and inclined to the tapes 11 and 12 in an upward and forward direction. The folds 55 20 and 21 have their doubled-up portions fastened by stitches 22 and 23 to the body 10

of the brassière. On the inner side of the lower back portion extending between the tapes 11 and 12 and the permanent folds 20 and 21 are arranged elastic bands 25 and 26 60 attached at their forward ends by stitches 27 and 28 to the folds 20 and 21 and fastened at their rear ends by stitches 29 and 30 to the tapes 11 and 12, the said stitches 29 and 30 forming part of the stitches used for fastening the tapes 11 and 12 to the ends of the body 10. The folds 20 and 21 assist in causing the device to properly conform to the body and also serve to enclose or hide the adjacent ends of the elastic bands 25 and 26, 65 between the material of the body 10 and the folds 20 and 21 respectively. The elastic bands 25 and 26 are arranged to hold the lower back portions 35, 36 of the body 10 encompassed by the said bands in a slack 70 condition, but when the brassière is donned and the fastening devices 13 and 14 are moved into engagement with each other to close the brassière at the back then the elastic bands 25 and 26 are stretched until the 75 slack in the lower back portions 35 and 36 is completely taken up. Thus the elastic bands 25 and 26 are under tension when the garment is worn and hence an exceedingly snug fit of the brassière on the wearer's 80 body is had.

By reference to Figure 1, it will be noticed that the lower edge portion of the brassière 85 fits over the upper rear portion of the corset 40, that is, the elastic bands 25 and 26 90 partly overlie the corset and the nether garment 41, and, on account of being held under tension and in firm engagement with the corset 40 and the nether garment 41, the brassière is not liable to slip or creep up on 95 the wearer's body and at the same time wrinkling of the body 10 is prevented especially at the back lower portions 35 and 36.

It will be noticed that by insuring a snug 100 fit of the brassière on the wearer's body the outer garment overlying the brassière can be fitted snugly to insure a proper hang and a close fit.

Having thus described my invention, I 105 claim as new and desire to secure by Letters Patent:

1. A brassière, comprising a body of inelastic material and having fastening members at the ends to close the brassière at the back, and elastic bands attached at their ends 110 to the inside of the lower back portions of the said body, the said lower back portions

encompassed by the said elastic bands being normally slack, the said elastic bands on closing the brassière being stretched and taking up the slack in the said lower back portions.

2. A brassière, comprising a body of a single piece of inelastic material, tapes attached to the inside of the ends of the said body and provided with fastening members for closing the brassière at the back, the said body having tapering permanent folds each spaced from the corresponding tape and at an angle thereto, and elastic bands each attached at its ends to the corresponding tape and the adjacent fold, the elastic bands extending across the inner sides of the lower back portions of the body and holding the

said lower back portions normally slack, and said elastic bands on closing the brassière being stretched and taking up the said slack in the lower back portions.

3. A brassière comprising a body of inelastic material and having fastening members at the ends thereof to close the brassière at the back, the said body having outwardly extending folds spaced from each end, and elastic sections encompassing the lower back portions of the body between the ends and said folds, said elastic sections being secured at the ends of the body and beneath the folds and the material of the body between the anchored ends thereof being normally slack.

ABHAHAM ZWIEBELSON
